UNITED STATES PATENT OFFICE.

GEORGE A. WHEELER, OF BROOKLYN, NEW YORK.

MOVING SPIRAL STAIRWAY.

No. 889,080.

Specification of Letters Patent.

Patented May 26, 1908. ■

Application filed October 14, 1905. Serial No. 282,783.

To all whom it may concern:

Be it known that I, GEORGE A. WHEELER, a citizen of the United States, residing in Brooklyn, New York, have invented certain 5 Improvements in Moving Spiral Stairways, of which the following is a specification.

My invention relates to certain improvements in what is known as a moving stairway, in which the step sections travel on inclined 10 ways so as to carry a person from one floor to another.

The invention particularly relates to that 15 class of stairways known as spiral stairways in which the step sections travel in a spiral course.

The object of my invention is to so construct a stairway of this type that it will occupy but a minimum of space and will form an ascending and descending flight in one 20 endless belt capable of conveying passengers or freight from a lower to a higher level, or from a higher to a lower level.

My invention can be mounted between two floors of a building or can be arranged to 25 carry passengers from one floor of a building to another, or from the street level to the platform of a railway, either elevated or depressed.

A further object is to so construct the step 30 sections that they will present a minimum of frictional resistance to their propulsion in traveling in a spiral course and to so construct the step sections that the exposed tread surface will be the full width even when 35 the step sections are traveling in the spiral course, and a still further object of the invention is to provide a suitable hand rail for the stairway, as fully described hereafter.

In the accompanying drawings:—Figure 1, 40 is a skeleton plan view showing the two spiral courses for the step sections and the upper horizontal section or platform in full lines and the lower horizontal section or platform in dotted lines; Fig. 2, is a diagram 45 view in elevation showing the position of the step sections; Fig. 3, is a plan view partly broken away showing the positions the steps assume as they travel in the spiral course; Fig. 4, is a plan view showing the position the 50 steps assume as they travel on the straight horizontal course, the tread surface of the steps being on the same plane; Fig. 5, is an end view of Fig. 3; Fig. 6, is an end view of Fig. 4; Fig. 7, is a sectional view on the line 7—7, 55 Fig. 4; Fig. 8, is a sectional view through the

center of the step section and taken at the point where the spiral path joins the upper straight horizontal path; Fig. 9, is a sectional plan view of Fig. 8, showing one method of driving the moving portion of the 60 stairway; Fig. 10, is a perspective view of one of the step sections; Fig. 11, is a sectional view through the hand rail; Figs. 12, 13 and 14, are views of modifications of details of my invention; and Fig. 15, is a view 65 showing a modification of the guides for the step sections.

In order to avoid confusion, I have not shown the supporting structure, or permanent framework for the stairway, in detail. 70

It will be understood that the framework will vary considerably according to the location of the stairway.

My improved stairway consists of two similarly turned spirals, each having an inner 75 and an outer track in the form of helical curves. On these two tracks the step sections are mounted. The helical curve tracks are connected at the top and bottom by horizontal tracks, preferably straight and arranged tangentially, thus making an endless 80 trackway for the step sections to travel on.

It will be noticed on referring to Fig. 1 that my improved spiral stairway has the form of a figure 8, and that the inner track 85 of the ascending spiral joins the outer track of the descending spiral and the outer track of the ascending spiral joins the inner track of the descending spiral. In each case the junction is preferably made by means of 90 short curves which render the transition from the incline to the horizontal, or from the horizontal to the incline, gradual.

It will be evident that the distance between the two spirals may be varied according 95 to circumstances, by lengthening the straight horizontal sections.

In the drawings, the framework consists of two plates A, A'; one forming the outer 100 helical curve and the other the inner helical curve between which the moving portion of the stairway travels. On these plates, as illustrated in Fig. 7, are rails a and a' secured to the plates by brackets, or by other suitable means. The moving portion consists of a series of step sections B, of the form clearly illustrated in Fig. 10. Each step section has a flat tread surface b and curved risers b' and b''. It will be noticed that the 105 riser b' curves inward at the end x of the step 110

section and curves outward at the end x' , while the riser b^2 curves outward at the end x and inward at the end x' .

The object of this construction is to make a step section in which the tread portion is rectangular and of the same width throughout and to allow one end of one tread section to overlap the end of the other tread section when traveling in the spiral path, yet allowing the step sections to assume a position on the horizontal or platform portion of the stairway with the surfaces on the same plane and their edges abutting as indicated in Fig. 4.

15 The framework of each step section consists of four brackets b^3 to which the tread plate b is secured, as well as the two riser plates b' and b^2 , as clearly illustrated in Fig. 7, of the drawings. Extending through the 20 brackets of each step is a single shaft C on which are mounted flanged wheels c , c' . The wheels c are arranged to travel on the rails a , while the wheels c' are arranged to travel on the rails a' . In this construction 25 there is only one wheel on each end of each step section, thus materially decreasing the friction as the step sections travel on the curved portion of the stairway. The step sections are held rigidly on the horizontal 30 portions of the structure by the edges of the step being in contact one with the other, as illustrated in Fig. 4, and are prevented from tilting while on the curved portion of the structure by bars, which will be described in 35 detail hereafter.

Depending from the center of each step section is a post D , clearly shown in Figs. 7 and 8. This post is secured to a frame D' , which is securely bolted to the brackets b^3 of 40 the step section in any suitable manner. The shaft C , in the present instance, passes through this frame D' , as indicated in Fig. 7.

On each post D are loosely mounted four sleeves e , e' and f , f' , and the sleeves are held 45 to the posts by a cotter pin, or other fastening d . Extending from the sleeve e are two arms e^2 , and extending from the sleeve f are two arms f^2 . These arms are of sufficient length to extend between two projections d' 50 on the step sections B and are for the purpose of bringing each step section in radial position while on the curved portion of the stairway. In the present instance, these projections d' are formed of rods screwed into the 55 central brackets b^3 and in order to reinforce the rods, the brackets have extensions b^4 which rest against the backs of the rods and resist the pressure of the arms. The arms e^2 also act as pivot pins for the links E , 60 which extend from the sleeve of one step to the sleeve of the other, while the arms f^2 form the pivot pins for the links F , which extend from one step to another, as indicated in Fig. 8. The links E are curved, as shown, 65 so as to avoid the risers of the step sections,

thus enabling the risers to be of the proper depth.

E' , E' are links which are mounted directly below the links E and extend from one sleeve e' to the other sleeve e' , while F' , F' 70 are links directly below the links F and extend from one sleeve f' to another sleeve f' , so that the several step sections are connected together by two sets of links alternately arranged, so that a parallel ruler joint 75 is formed; the posts and consequently the step sections always remaining vertical, while the step sections can either assume a position one above another, as in a flight of steps, or all on a horizontal plane, such as is 80 necessary at the platform, the two positions being clearly illustrated in Figs. 5 and 6 respectively, as well as in Fig. 8.

It will be noticed that the links E , E' and F , F' are arranged in pairs:—thus there are 85 four links extending from one step section to another and the connection is rigidly and securely made, so that it is impossible for one section to pull away from another to form gaps between the step sections. The lower 90 pair of links F' are connected together by a series of pins f^3 , which are preferably set radially, as illustrated in Figs. 3, 4 and 9, so that they will properly mesh with the driving sprocket wheels G and G' , which are 95 mounted on radial shafts G^2 and G^3 , driven in any suitable manner.

In referring to Fig. 7, it will be noticed that the links E , E' are closer to the center of their sleeves than the links F , F' . This arrangement allows one set of links to swing 100 clear of the other.

The driving wheels G and G' are preferably mounted so that they will contact with the toothed links F' at a point directly below the upper platform, as shown in Figs. 8 and 9, while the step sections are still on the curved portion of the stairway, thus insuring tight joint between the step sections where the inclined curved portion joins the horizontal 110 platform section of the stairway.

When the step sections are on the horizontal portion of the stairway the tread surfaces are all on the same line and the step sections are held rigidly while they travel, by 115 their edges coming in contact, one step section locking another and preventing any swinging movement which would be liable to occur on the posts.

When the sections are on either of the 120 spiral portions of the stairway then the extended arms are spread apart contacting with the projections on the underside of the step sections, locking the step sections and preventing them swinging on the posts. 125 These arms not only hold the step sections rigid but hold them rigid in their true radial positions when upon the spiral tracks.

In designing a stairway in which the step sections must travel up one spiral path and 130

down another, the step sections must be so shaped that there will be no gaps or spaces between the step sections while traversing any portion of the structure. By making 5 the step sections as clearly illustrated in Fig. 10 and as described above it will be noticed that the two risers of each step section are similar but oppositely placed. Taken in 10 cross section they are convex, the arc of their convexity varying according to the point in the length of the step at which it is measured and coincides in each case with the path through which a corresponding point on the edge of the next preceding or the next 15 succeeding step swings in relation to it in changing from one position to another at certain points in the stairway. Thus the step sections are always retained in close contact one with another throughout the 20 length of the step sections.

As will be seen by the drawings, the rails and the wheels of the step sections are concealed at all points throughout the stairway by sheathing a^2 , which extends down to a 25 short distance above the axles of the wheels. The sheathing on the spiral portion of the stairway is extended above the line of the steps to form the guard, one side acting as the hand rail support A^2 , which may be made 30 hollow, as clearly shown in Fig. 11.

I preferably so design the stairway that the incline will not terminate at the termination of the spiral, but extend slightly beyond that point so that the junction can be readily 35 made on straight lines rather than on the short curves, as clearly illustrated in the drawings.

In order to prevent any gaps or spaces being formed at the ends of the step sections, I 40 form a curved recess in each end of each step section, the curve corresponding to the short radius of the spiral so that the step section will fit close against the inner wall of the structure while traveling in the spiral path. 45 This would leave a gap at the outer end of the step section and in order to close this gap I provide slides $h h'$ which have a limited movement directly under the tread surface of each step section. The outer edge of each 50 slide is curved to correspond with the long radius of the spiral so that it will fit against the outer wall of the spiral portion of the structure.

I preferably unite the two slides $h h'$ of each 55 step section by rods h' , which extend through the brackets of the step sections, the brackets acting as supports for the rods and the slides, so that when the slide at one end of the step section is pushed in the slide at the opposite 60 end of the section is pushed out.

When the step sections are traveling on the horizontal portion then the two slides are in the mid-position, as indicated in the drawings, practically closing the gaps which would 65 otherwise form at this point.

It will be noticed in Fig. 1, of the drawings, that I inclose the stairway with a railing on each side, leaving a space at the upper and lower platforms for a passage. The hand rails at the inner portions of the stairway can 70 be fixed, but I prefer to provide a separate moving hand rail on the ascending run of the stairway and another one on the descending run of the stairway. This moving hand rail J travels in guides a^3 on the outer railing, as 75 shown in Figs. 8 and 9, the moving hand rail terminating at the upper and lower platforms.

In the present instance the hand rail consists of an endless belt J made up of two coils 80 of spirally wound spring wire $j j'$ one interlaced with the other, the coil j being preferably of greater diameter than the coil j' and of heavier wire.

In winding the coils they are preferably 85 given a permanent set or curvature corresponding with the radial distance of the hand rail when in position from the center of the spiral, but in some instances the coils may be wound without such curvature, as the flexibility of the hand rail is such that it will readily accommodate itself to any necessary curvature.

The hand rail J passes around wheels, at 90 top and bottom of each flight and the shafts of these wheels are mounted in journal boxes. The wheels or sheaves at the top of the flight are preferably the driving sheaves and those at the bottom idlers.

The traveling hand rail projects above the 100 railing, as indicated in Figs. 8 and 11 and is preferably driven at the same speed and in the same direction as the step sections, the return run of the hand rail passes through the railing and may be supported at intervals 105 by rollers j^2 .

The driving wheels or sheaves may be provided with teeth to engage with strands of the spirally wound wire, or I may depend upon the frictional contact between the 110 sheaves and the hand rail to drive the latter. The sheaves may be driven by a belt or chain from a wheel or sprocket on one of the shafts upon which a sprocket which drives the steps is keyed or otherwise fastened.

I may in some instances cover the exposed 115 portions of the hand rails with flexible material, but this is not absolutely necessary.

In some instances in place of the hand rail made of coiled wire I may use a hand rail 120 having a rubber face and mounted on a link chain, the chain and the rubber face having a permanent set or curvature to coincide with the spiral path in which it must travel.

This improved hand rail is set forth and 125 claimed in a companion application filed by me on the 13th day of November 1905, Serial Number 287,054, and I therefore do not claim it in the present application.

I may modify the drive, as illustrated in 130

Fig. 12, by extending the heels of the rack links, as illustrated in said figure, so that they just clear one another and form a continuous rack. In this instance a single toothed wheel may be used to mesh with the rack directly under the upper or lower platform or both, as the case may be. The rack in this instance is made solid, the teeth being formed on the links.

10 Instead of using the link plates connected by pins which act as teeth I may make the links each from a single casting, as illustrated in Fig. 14, a single link being used in place of the two links illustrated in Figs. 8 and 9.

15 I may, in some instances, cut teeth on the edges of the link elements, as shown in Fig. 13, when it is desired to drive by one wheel engaging the cross pins and another wheel or wheels engaging the teeth on the edge of 20 the links. The drive, however, will depend upon the location and size of the stairway.

25 In Fig. 15, I have shown a modification. Instead of the step sections leaving the spiral section on a tangent as illustrated in Fig. 1, it may leave it on a curve of larger radius and then from a tangent on this curve. In fact the guides for the step sections, as well as the shape of the riser portions of the steps will vary according to location and arrangement of parts, as I want at all times to make 30 a tight joint between the step sections throughout the entire run of the stairway.

It will be seen by the above construction 35 that I am enabled to build a spiral stairway with one pair of tracks and step sections, each having a single wheel at each end arranged to travel on the tracks, thus the step sections travel with a minimum friction and by connecting the step sections by parallel 40 links I insure the treads being always in a horizontal plane at every point throughout the course. Furthermore I am enabled to use a comparatively wide tread on the spiral portion of the stairway owing to the peculiar 45 shape of the treads of the step sections, whereby one step section will overlap another.

The drive is simple and economical as the 50 step sections are each connected to the drive chain at a central point, thus dispensing with complicated driving mechanism which is one of the great difficulties to overcome in this class of moving stairways. The step sections may be driven at any point desired either as 55 they travel the spiral path or as they travel the horizontal path.

I claim as my invention:—

1. The combination in a moving stairway, 60 of two spiral guides connected at top and bottom by horizontal sections, step sections having rectangular treads and shaped to travel in an endless path up one spiral and down the other spiral, and means including a double chain for driving said sections, substantially as described.

2. The combination in a moving stairway, 70 of two similarly turned spiral guides each having an outer and an inner track, horizontal portions connecting the two spirals at top and bottom, step sections having rectangular treads arranged to travel in the endless path formed by the spirals and the horizontal portions, and means for driving the said sections, substantially as described.

3. The combination in a moving stairway, 75 of two similarly turned spiral guides, each having an inner and an outer track in the form of helical curves, horizontal tracks at top and bottom of the stairway connected to the spiral tracks, rectangular tread step sections 80 having wheels arranged to travel on said tracks, an endless chain to which each step is pivoted, and means for driving the chain so that the step sections, will travel in an endless path, substantially as described. 85

4. The combination in a moving stairway, 90 of two similarly turned spirals, each having an inner and an outer track in the form of helical curves, horizontal tracks at top and bottom connecting the tracks of the two 95 spirals, the inner track of the ascending spiral joining the outer track of the descending spiral and the other track of the ascending spiral joining the inner track of the descending spiral, step sections arranged to travel 100 on the said endless track, and means for driving the said step sections, substantially as described.

5. The combination in a moving stairway, 105 of two similarly turned spiral guides connected together at top and bottom by horizontal sections, step sections each having flat treads and curved risers at each side, said curved risers being such that the steps will be close together on the elevating and return 110 runs as well as on the horizontal runs, and means for driving said step sections, substantially as described.

6. The combination in a moving stairway, 115 of two similarly turned spiral guides connected together at top and bottom by horizontal sections, step sections each having curved risers at each side, the curves of the risers being such that the step sections will be close together while their relative positions are changing, and means for driving said step sections, substantially as described.

7. The combination in a moving spiral 120 stairway, of similarly turned spiral guides, a single guide rail at each side of the fixed portion of the spiral stairway, step sections each having a single wheel at each end arranged to travel on said rails, means for retaining the step sections in a horizontal position, and means for driving said step sections, substantially as described.

8. The combination in a spiral stairway, of 125 step sections, guides therefor and means for moving said step sections, each step section having a flat tread, and a curved riser at 130

each side, each of said risers projecting at the base at one end of the step section and projecting at the tread at the opposite end thereof, substantially as described.

5 9. The combination in a spiral stairway, of step sections, guides therefor and means for moving said step sections, each step section having a flat tread and a curved riser at each side, one riser projecting at the base at one 10 end of the step section and the other riser projecting at the tread at said end, and vice versa, substantially as described.

10 10. The combination in a spiral moving stairway, of spiral guides, step sections arranged to travel on said guides, said step sections having rectangular treads, the tread of one step section overlapping the tread of the one below it at the inner edge of the stairway as the step sections travel on the curved rails, 20 with a double chain for driving said stairway, substantially as described.

25 11. The combination in a stairway, of guides, step sections arranged to travel on said guides, each step section having a depending post, with links pivoted to swing in two planes at right angles to each other, and extending from one post to another, substantially as described.

30 12. The combination in a spiral stairway, of spiral guides, step sections arranged to travel on said guides, a post on each step section, two sets of links connecting the posts, and means for driving the said sections, substantially as described.

35 13. The combination in a spiral stairway, of spiral guides and horizontal guides, sections arranged to travel over both guides and arranged in step form on the spiral portion and flat on the horizontal portion, links 40 connecting the sections together, said sections being free to swivel on vertical axes, substantially as described.

45 14. The combination in a spiral stairway, of guides, step sections arranged to travel on said guides, posts projecting from each step section, sleeves on the posts, and links connecting the sleeves of the several posts so as to form an endless chain, substantially as described.

50 15. The combination in a spiral stairway, of spiral guides, step sections each having a single wheel at each end arranged to travel on the guides, a central post on each step section, sleeves mounted on the posts, and links 55 connecting the sleeves of the several posts, substantially as described.

60 16. The combination in a stairway, of guides, step sections arranged to travel on said guides, posts projecting from said step sections, sleeves on the posts, and links connecting the sleeves, substantially as described.

65 17. The combination in a stairway, of guides, step sections arranged to travel on said guides, posts projecting from said step

sections, two sets of sleeves on each post, and two sets of links connecting the sleeves forming an endless chain, substantially as described.

18. The combination in a stairway, of 70 guides, step sections arranged to travel on said guides, a post projecting from each step section, two sets of sleeves swiveled on each post and two sets of links connecting the sleeves forming an endless chain so that the 75 step sections are free to swivel on the links and free to assume different planes in respect to each other, and means for making the steps assume a radial position on the curved portion of the stairway, substantially as de- 80 scribed.

19. The combination in a stairway, of 85 guides, step sections arranged to travel on said guides, links connecting the step sections forming an endless chain, the alternate links having teeth arranged to be engaged by the driving means, substantially as described.

20. The combination in a moving stairway, 90 of guides, step sections arranged to travel on said guides, posts depending from each step section, sleeves on the posts, two sets of links alternately arranged and pivoted to the sleeves forming an endless chain, the lower links of each alternate set having teeth, with driving mechanism engaging the said toothed 95 links, substantially as described.

21. The combination in a spiral stairway, 100 of guides, step sections arranged to travel on said guides, links connecting the step sections and forming an endless chain, each alternate link having gear teeth, and two gears arranged to engage the toothed links and so arranged that one gear will always be in mesh with the endless chain, substantially as described. 105

22. The combination in a spiral stairway, 110 of guides, step sections arranged to travel on said guides, posts depending from said step sections, two sets of links connecting the posts, the upper link of each alternate set being curved to clear the riser of the step section, substantially as described.

23. The combination in a spiral stairway, 115 of step sections, guides therefor, each step section having a gap closing slide at one end, substantially as described.

24. The combination in a spiral stairway, 120 of step sections, guides therefor, each step section having a gap closing slide at each end, substantially as described.

25. The combination in a spiral stairway, 125 of step sections, guides therefor, each step section having gap closing slides at each end connected together so that when a slide is forced into the step section at one side the other slide is projected, substantially as described.

26. The combination in a double spiral 130 stairway, of step sections, guides therefor, each step section having a curved recess at

each end, with slides arranged to be projected to close said recess, each slide having a curved edge, substantially as described.

27. In a device of the class described, the combination with tracks having straight and curved portions, a series of steps, parallel link connections of constant length between said steps arranged to permit their axes to remain at right angles to the line of movement of said steps at every portion of the track, and means for driving the steps, substantially as described.

28. In a device of the class described, the combination with tracks comprising straight and laterally curved portions, of a series of steps having rectangular tread surfaces, link connections of constant length between said steps arranged to permit their axes to remain at right angles to the line of movement of said steps at every portion of the track, and means for driving the steps, substantially as described.

29. In a device of the class described, the combination with a pair of tracks having horizontal and inclined portions and the necessary lateral curves to make a complete circuit, of a series of steps each having a pair of supports coöperating with said tracks and free to turn on a vertical axis, with a system of parallel links having a constant length connecting said steps and arranged to hold their tread surfaces in a horizontal position on the horizontal and inclined portions of the track, means for driving said steps, and means for limiting the amount of turning of the steps on their vertical axes, substantially as described.

30. In a device of the class described, the combination with a pair of tracks including horizontal and inclined portions and the necessary lateral curves to make a complete circuit, of a series of steps each provided with a pair of supports coöperating with said tracks, a system of parallel links of constant length connecting said steps so as to hold their surfaces in a horizontal position on the horizontal and inclined portions of the track, and means for driving said steps, substantially as described.

31. In a device of the class described, the combination with a pair of tracks including horizontal and inclined portions and the necessary lateral curves to make a complete circuit, of a series of steps each provided with a single pair of supports coöperating with said tracks, and a system of links connecting the central portions of said steps and located entirely beneath them, substantially as described.

32. In a device of the class described, the combination with tracks including horizontal and inclined portions and the necessary lateral curves to make a complete circuit, of a series of steps coöperating therewith, links of constant length connecting said steps and

mounted so as to be free to swing in two planes substantially at right angles to each other, said links being provided with rack teeth formed thereon, and a driving pinion engaging the teeth of said links, substantially as described.

33. In a device of the class described, the combination with tracks including horizontal and inclined portions and the necessary lateral curves to make a complete circuit, of a series of steps each provided with a pair of supports coöperating with said tracks, parallel links of constant length connecting said steps and provided with rack teeth formed thereon, and a driving pinion engaging the teeth of said links, substantially as described.

34. In a moving stairway, an endless series of step sections connected together at the intersection of their longitudinal and transverse axes and capable of swinging relatively to each other, in two planes at right angles to each other, substantially as described.

35. In a moving stairway, the combination with tracks having straight and laterally curved portions, of a series of steps, link connections of constant length between said steps arranged to permit their axes to remain at right angles to the line of movement of the steps at every portion of the track and the centers of their axes to remain at a uniform distance apart, and means for driving said steps, substantially as described.

36. A moving stairway including a chain, steps mounted thereon, a guide, means for driving the chain, arms on the chain, and stops on the steps placed to coöperate with said arms to maintain said steps in predetermined positions on the curved portions of the guide, substantially as described.

37. The combination in a moving stairway of steps, guides for the steps including curved portions, a chain having its members movably connected to the steps, and coöperating devices carried by the steps and chain for determining the positions of the steps upon the curved portions of the guides, substantially as described.

38. The combination in a moving stairway of a series of steps each having a projecting post, a chain connected to the steps, a plurality of sleeves on each post, a projecting arm or arms for each sleeve, stops on the steps placed to coöperate with said arm or arms to limit the possible movement of the steps relative to the elements of the chain, a guide for the steps, and means for driving the chain, substantially as described.

39. The combination in a moving stairway of a guide, steps mounted thereon and each provided with a post, sleeves mounted on each post, an arm or arms attached to each sleeve, a chain having its links connected to said arms as pivots, and stops on the steps placed to coöperate with said arms to determine the positions of the steps upon the

curved portions of the guide, substantially as described.

40. In a moving stairway, the combination of a pair of rails consisting of horizontal and inclined portions and the necessary lateral curves to make a complete circuit, of a series of step sections each provided with a pair of supports coöperating with said rails, stops on the step sections, links pivoted to said 10 step sections, and arms connected with said links and engaging said stops, substantially as described.

41. In a moving stairway the combination of step sections, a chain connecting said sections so as to permit them to swing on vertical axes, with arms and coöperating stops placed to limit the swing of the step sections, substantially as described.

42. In a moving stairway the combination 20 of a chain, a series of step sections connected

to said chain so as to be free to turn on both horizontal and vertical axes, a series of laterally extending arms connected with the chain and pivoted to the step sections, and stops on the step sections coöperating with said 25 arms, substantially as described.

43. The combination of a moving spiral stairway, with a hand rail support and a moving hand rail arranged to travel on said support, said hand rail having a permanent 30 set or curvature so to travel readily in the spiral path, substantially as described.

In testimony whereof, I have signed my name to this specification, in the presence of two subscribing witnesses.

GEORGE A. WHEELER.
